UNITED STATES PATENT OFFICE.

JULIUS H. T. OLSEN, OF NEW YORK, N. Y.

SHOE POLISH.

No Drawing.

Application filed December 3, 1921. Serial No. 519,657.

To all whom it may concern:

Be it known that I, JULIUS H. T. OLSEN, a citizen of Denmark, and a resident of the borough of Manhattan, in the county of 5 Bronx and State of New York, have invented certain new and useful Improvements in Shoe Polish, of which the following is a specification.

This invention relates to improvements in 10 shoe polish, particularly the kind adapted for use on white shoes.

Among other objects of my invention is to provide in a polish, a binder which after it has been applied prevents the other ingredients 15 of which the polish is comprised of, of coming or rubbing off.

Another object of my invention is to provide as an article of manufacture, a polish which when applied particularly to the 20 surface of a white shoe, assumes a snow white color and when dry will not rub or come off.

These and other objects are attained by the novel combination of ingredients hereinafter described.

At the present time shoe polish is composed of such ingredients that after being applied to the surface of a white shoe and 25 permitted to dry, presents a coating, which on account of its unbonded state, readily comes off, so that when anything, for instance, an article of clothing comes slightly 30 in contact with the surface of the shoe the coating rubs or comes off and transfers onto the article. The smooth coating which exists 35 on the surface of the shoe is by such contact removed and the article of clothing becomes soiled.

I have found by introducing a gummy or 40 other similar binding substance in the mixture, forming the white polish, the new mixture formed when applied and allowed to dry will not come or rub off from the sur-

face of the shoe and will cause a white smooth preserved coating to be formed on 45 the surface.

In making up the mixture I preferably use gum arabic, dissolved in water as a binder, and zinc white as the base. I have found that by dissolving two ounces of gum 50 arabic in two quarts of water and adding to this three-quarter ($\frac{3}{4}$) of a pound of zinc white, a mixture is obtained which when applied and allowed to dry, produces a snow white coating which will not come off.

Be it understood that I do not confine myself to any particular base for by using the proper base a shoe polish can be produced which will be particularly adapted for black, tan or any other color shoe, and I do not confine myself to the specific proportions mentioned above, and although I preferably use 55 gum arabic as a binder, any other gummy or viscous material may be used.

Having thus described my invention, what I claim as new and desire to secure by Letters Patent, is:—

1. A white shoe polish consisting of a viscous binder, and zinc white mixed therewith.
2. A white shoe polish consisting of dissolved gum arabic, and zinc white mixed therewith.
3. A shoe polish consisting of an admixture of gum arabic, zinc white and a coloring material.
4. A white shoe polish consisting substantially of two ounces of gum arabic dissolved in two quarts of water, mixed with 12 ounces of zinc white.

Signed at New York, in the county of 80 New York and State of New York, this 31st day of October, 1921.

JULIUS H. T. OLSEN.
